UNITED STATES PATENT OFFICE.

GYÖRGY VAJDA, OF LANDISVILLE, PENNSYLVANIA.

KEYLESS LOCK.

Specification of Letters Patent. Patented Apr. 18, 1916.

1,179,683.

Application filed May 21, 1915. Serial No. 29,497.

To all whom it may concern:

Be it known that I, GYÖRGY VAJDA, a subject of the King of Hungary, residing at Landisville, in the county of Lancaster and 5 State of Pennsylvania, have invented certain new and useful Improvements in Keyless Locks, of which the following is a specification.

This invention relates to new and useful 10 improvements in keyless locks.

The primary object of the invention is to provide a door lock presenting such complicated exterior appearance as to deceive an unauthorized person with respect to its 15 correct manipulation although being readily operated by an authorized person familiar with the workings thereof.

A further object is to provide a door lock operable from either side thereof without 20 the employment of a key and having reversing connections between the locking bolt and the catch with which the lock is provided.

A still further object is to provide a keyless door lock having a knob actuated catch 25 and being provided with reversely acting operating connections between the lock catch and bolt, the bolt being retained in either projected or retracted position as de- 30 sired.

With these general objects in view and others that will appear as the nature of the invention is better understood, the same consists in the novel combination and arrangement of parts hereinafter fully described, 35 illustrated in the accompanying drawings and then claimed.

In the drawings forming a part of this application and in which like designating 40 characters refer to corresponding parts throughout the several views:—Figure 1 is an elevational view of the lock detached, with the side plate of the casing removed and parts being broken away, the bolt being shown retained in its retracted position. Fig. 2 is a similar view but with the bolt 45 illustrated in its retained projected locking position. Fig. 3 is a transverse sectional view through the device showing the catch mechanism. Fig. 4 is a longitudinal sectional view thereof showing the elements positioned as illustrated in Fig. 1. Fig. 5 is a view similar to Fig. 4 but with the elements 50 illustrated as shown in Fig. 2. Fig. 6 is a perspective view of the spring catch member 55

detached. Fig. 7 is a similar view of the locking bolt. Fig. 8 is a perspective view of the sliding block employed in connection with the catch, and Fig. 9 is a perspective view of the operating shaft detached with 60 its arm members.

In the construction of the present lock, a casing 10 is provided of substantially the usual form and has a stationary spindle 11 extending therethrough and provided 65 upon its opposite ends with sham knobs 12 at opposite sides of the lock, the entire structure being rigid with the casing and merely serving to confuse an unauthorized person by the plurality of knobs.

A catch 13 of the form best illustrated in Fig. 6 is slidably mounted through an opening 14 in the front wall 15 of the casing, while a locking bolt 16 as best illustrated in Fig. 7 is slidably mounted through an opening 17 in the said front wall.

Opposite knobs 18 are arranged exteriorly of the casing 10 secured to the opposite projecting ends of a spindle 19 journaled through the casing, the said knobs 80 being adapted for retracting the catch 13 by means of an arm 20 carried by the spindle 19 interiorly of the casing and freely seating within a slot 21 in the adjacent side of the catch 13.

The bolt 16 slidably mounted within a frame 22 within the casing, is provided with a projecting side rib 23 which is engageable at its opposite ends by the crank 24 of a shaft 90 25 journaled through the casing and having oppositely arranged operating turn buttons 26 secured thereto. When the bolt 16 is projected to its locking position as illustrated in Figs. 2 and 5 of the drawings by the mechanism hereinafter described, either of the buttons 26 may be turned for engaging the crank 24 with the inner end of the bolt rib 23 thus retaining the bolt projected, while similarly, when the bolt is retracted as illustrated in Figs. 1 and 4 of the drawings the buttons 26 may be reversely turned for engaging the crank 24 with the forward end of the rib 23 thereby retaining the bolt 100 in its inoperative retracted position.

The active operative means for the bolt 105 and catch and whereby the same may be reversely actuated consists of an operating shaft 27 journaled through the opposite sides of the casing 10 and a pane perpendicular to that of the spindles 11 and 19,

the said shaft having a catch actuating arm 28 and a star wheel form of triple lever arms 29.

- 5 The catch 13 is slidably mounted within a frame 30 while a block 31 is slidably mounted within the same bracket and inwardly thereof. An expansion spring 32 is arranged between the adjacent ends of the said catch 13 and block 31 being secured to each of the same and functionally acting as a resilient projecting member for the said catch when the bolt is retracted and for a connecting withdrawing means for the catch when the bolt is projected.
- 10 15 The locking casing 10 is provided with oppositely arranged projecting bosses 33 each having a central bore 34 while similar plungers 35 and 36 are arranged within the said bores, each of the said plungers 20 having a handle or operating knob 37 upon its outer end. The plunger 35 is connected by means of a link 38 with the arm 39 of the star wheel 29 while the opposite plunger 36 is similarly connected to the adjacent 25 arm 40 of the said star wheel by means of a connecting rod 41.

The arm 28 of the operating shaft is connected to a rocker arm 42 pivoted upon a transverse rod 43 of the casing 10 by means 30 of a link 44, while the opposite end of the arm 42 is pivotally attached to the inner free end of a lug 45 projecting from the aforementioned block 31.

35 The third arm 46 of the star wheel is pivotally connected to the rear end of the bolt 16 by means of a connecting rod 47.

40 From this detailed description of the complete device, the normal position of the elements as shown in Fig. 1 will be at once apparent, the knobs 18 being employed for retracting the catch 13 whenever desired, thus compressing the spring 32 and allowing the catch to return to its projected position when released by the said knobs. When the catch 45 is projected and the bolt retracted, the two plungers 35 and 36 will be inwardly positioned and an outward pull then exerted upon either of the operating knobs 37 will turn the shaft 27 through the agency of the 50 star wheel 29 to the position shown in Fig. 2 which effects a projecting of the bolt by means of the star wheel arm 46 and the connecting member 47, while the catch is retracted by pulling inwardly upon the block 55 31 by means of the arm 28 and the operative connections of the rocker arm 42 between the same and the said block.

50 The buttons 26 are employed for retaining the locking bolt in either its retracted or projected position as desired and when the crank 24 is released from its engagement with the bolt rib 23, the plungers 35 may be withdrawn for projecting the bolt and reTRACTING the catch as hereinabove set forth 65 or either of the plungers 35 and 36 may be

forced inwardly for retracting the bolt and projecting the said catch.

70 While the form of the invention herein shown and described is what is believed to be the preferred embodiment thereof, it is nevertheless to be understood that minor changes may be made in the form, proportion and details of construction without departing from the spirit and scope of the invention as set forth in the appended claims.

75 What I claim as new is:—

1. A keyless lock comprising a casing, a 80 slideable bolt and catch carried thereby, simultaneous operating means for the said catch and bolt, movement reversing connections between the said operating means and the catch and bolt, engageable projection and retraction retaining means for the bolt carried by the said casing, operating buttons for the said retaining means positioned at 85 opposite sides of the casing, independent resilient positioning means for the said catch, and independent knob operating retracting means for the said catch.

2. A lock comprising a casing, a projectable bolt slidably mounted therein, an operating shaft journaled through the said casing, operative connections between the said shaft and bolt, oppositely arranged plungers carried by the casing, operative 95 connections between the said plungers and shaft, a sliding catch within the said casing, a 100 slideable block spaced from the said catch and mounted within the casing, an expansion spring connecting the said catch and block, operative connections between the said shaft and block and independent means for retracting the catch.

3. A lock comprising a casing, a projectable bolt mounted within the said casing 105 and having a side rib projecting therefrom, operating means for the said bolt, a shaft journaled through the said casing and having a crank portion adapted to engage either end of the rib and opposite operating 110 buttons for the said crank shaft arranged at opposite sides of the casing.

4. A lock comprising a casing, opposite bosses carried by the casing and having central bores, laterally shiftable plungers 115 within the said bores, an operating shaft journaled through the said casing, a star wheel lever secured to the said shaft, link connections between two adjacent arms of the said lever and the said plungers, a projectable slide bolt carried by the casing, a pivotal connecting link between the third arm of the said lever and the adjacent end of the said bolt, a sliding catch operatively connected to said star wheel, and means 125 operating independently of the bolt operating means for retracting the catch.

5. A lock comprising a casing, opposite bosses carried by the casing and having central bores, laterally shiftable plungers 130

within the said bores, an operating shaft journaled through the said casing, a star wheel lever secured to the said shaft, link connections between two adjacent arms of the said lever and the said plungers, a projectable slide bolt carried by the casing, a pivotal connecting link between the third arm of the said lever and the adjacent end of the said bolt, a catch slidably carried by the said casing, a slidable block within the casing, an expansion spring connection be-

tween the said block and catch, a rocker arm pivotally mounted within the casing, a lug carried by the said block having its free end pivotally connected with one end of the said rocker arm, a single arm upon the operating shaft, and a pivotal link connection between the said single arm and the other end of the said rocker arm. 15

In testimony whereof I affix my signature. 20

GYÖRGY VAJDA.
